ILLUMINABLE PICTURE FRAME

Sylvan Corwin, Elmhurst, N.Y.

Application February 17, 1959, Serial No. 54,644

Term of patent 14 years

(Cl. D29—20)

Fig-1

Fig-2

FIG-3

FIG-4

Fig. 1 is a front elevational view of an illuminable picture frame; Fig. 2 is a side elevational view thereof; Fig. 3 is a top plan view thereof; and Fig. 4 is a rear perspective view.

I claim:

The ornamental design for an illuminable picture frame, substantially as shown.
